Primary Examiner — Kendra Leslie Hamilton*Assistant Examiner* — Elizabeth S Struble(74) *Attorney, Agent, or Firm* — Schwegman Lundberg & Woessner, P.A.(57) **CLAIM**

The ornamental design for an exoskeleton for a respirator mask, as shown and described.

DESCRIPTION

FIG. 1 is a front view of an exoskeleton for a respirator mask according to our new design,

FIG. 2 is a back view thereof,

FIG. 3 is a left side elevational view thereof,

FIG. 4 is a right side elevational view thereof,

FIG. 5 is a top plan view thereof,

FIG. 6 is a bottom plan view thereof; and,

FIG. 7 is a front perspective view thereof.
